UNITED STATES PATENT OFFICE.

WALTER I. KIRK AND LOUIS E. PETERSEN, OF CHICAGO, ILLINOIS, ASSIGNEES, BY
MESNE ASSIGNMENTS, TO MARQUETTE MUSIC COMPANY, OF CHICAGO, ILLINOIS,
A CORPORATION OF ILLINOIS.

STRINGED MUSICAL INSTRUMENT.

Application filed April 29, 1922. Serial No. 557,271.

To all whom it may concern:

Be it known that we, WALTER I. KIRK and LOUIS E. PETERSEN, citizens of the United States, residing at Chicago, in the county of Cook and State of Illinois, have invented a certain new and useful Improvement in Stringed Musical Instruments, of which the following is a full, clear, concise, and exact description, reference being had to the accompanying drawings, forming a part of this specification.

Our invention relates to stringed musical instruments and particularly to banjos and the like.

One of the objects of the invention is to provide a simple and advantageous form of stringed musical instrument.

Another object of the invention is to strengthen the tone and to make it of fine quality.

Another object of the invention is to secure strength, simplicity and rigidity of construction in instruments of the class specified.

Another object of the invention is to avoid built up constructions so common in musical instruments.

In the accompanying drawings Fig. 1 is a plan view of a stringed musical instrument such as a banjo embodying our present invention;

Fig. 2 is a cross section taken on line 2—2 in Fig. 1;

Fig. 3 is a cross section similar to Fig. 2 of a modified form of construction.

Referring to the drawings, we show a banjo A, although it will be understood that the invention may be applied to other forms of musical instruments. This banjo A has a neck 1 and a body or head 2, and strings 3—3. The head 2 has an annulus or ring 4 preferably made of a series of wooden pieces 4^a—4^a, as best shown in Fig. 2. It also has an annular member or ring 5 preferably made of metal and having a side portion 5^a which extends down and is on the outer side of the ring or hoop member 4. This member 5 has an annular bead 6 which forms a support for the vellum resonating member 7 and also has an inwardly extending concave portion 8 preferably made integral with the curved portion 6 and the outer side portion 5. The portion 8 extends upwardly toward the diaphragm 7 but does

not touch the same, there being a small space 9 between the upper edge of member 8 and the diaphragm 7.

A metal ring 10 holds the diaphragm in place by engaging a flesh hoop 11 on the same. Side hooks 12 engage the tension ring 10 to hold the same in position and are in turn engaged and held by brackets 13 secured by cross bolts 14 passing through rim member 4, and also through the side or skirt portion 5^a of the diaphragm support.

In the modification shown in Fig. 3 the member 5 has a side portion 5^b extended downwardly and underneath the lower edge of rim member 4 and is also preferably provided with a flange 5^c on the inner side of the rim member 4.

By this construction a very strong tone of very fine quality is obtained, the metal member 5 apparently strengthening the tone and giving it the quality. Furthermore the construction is much simplified and is also very strong and rigid, the shoulder 6 affording a strong and rigid support for the diaphragm.

It will be understood that changes and modifications may be made without departing from the spirit of the invention.

What we claim is:

1. A stringed musical instrument having a rim with an annular shoulder, a diaphragm extending across the rim, means for holding the diaphragm under tension and an annular member arranged beneath the diaphragm and extending around within said rim, and at the upper edge of the same, said annular member being concave with both its outer and inner edges near the diaphragm so as to form a resonating chamber beneath the diaphragm, the inner edge of said member being free from contact with the diaphragm.

2. A stringed musical instrument having a rim, a metal ring extending around the top of said rim and having a concave inwardly extending portion forming a resonating chamber and a diaphragm extending across said rim and above said resonating chamber, the concave side of said ring facing the diaphragm, and the inner edge of the same being free from contact with the diaphragm.

3. A stringed musical instrument having a rim of nonmetallic material, a metallic ring mounted on the top of said rim and having

a downwardly extending portion arranged outside of the rim and a concave portion extending inwardly from the top of the rim, the inner edge of said concave portion being extended up nearly to the diaphragm but being free from contact therewith, a diaphragm extending across the top of the rim

and of said metal ring and above said concave portion, and means for holding the diaphragm under tension.

10

In witness whereof, we hereunto subscribe our names this 1st day of April, A. D., 1922.

WALTER I. KIRK,
LOUIS E. PETERSEN.

Certificate of Correction.

It is hereby certified that Letters Patent No. 1,575,212, granted March 2, 1926, upon the application of Walter I. Kirk and Louis E. Petersen, of Chicago, Illinois, for an improvement in "Stringed Musical Instruments," were erroneously issued to "Marquette Music Company, of Chicago, Illinois," whereas said Letters Patent should have been issued to *Lyon & Healy, Inc., of Chicago, Illinois, a Corporation of Illinois*, said corporation being assignee, *by mesne assignments, of the entire interest* in said invention, as shown by the record of assignments in this office; and that the said Letters Patent should be read with this correction therein that the same may conform to the record of the case in the Patent Office.

Signed and sealed this 13th day of April, A. D. 1926.

[SEAL.]

M. J. MOORE,
Acting Commissioner of Patents.
